UNITED STATES PATENT OFFICE.

DOUGLAS G. HARVEY, OF DIXON, ILLINOIS.

WOVEN-WIRE FABRIC.

Application filed July 28, 1921. Serial No. 488,093.

My invention relates to an improvement in woven wire fabric, and particularly to improved means for marking this fabric in designated lengths to assist in marketing the material. My invention will be more readily understood from the following description thereof in connection with the accompanying drawings, in which—

Figure 1 is a perspective view of a roll of woven wire fabric embodying the features of my invention.

Figure 2 is an enlarged detail showing the manner in which the fabric is marked.

In the drawing, I have shown a strip 3 of woven wire fabric which is marked at designated intervals by a distinctive marking, so that a predetermined length of this material can be quickly and readily measured off. In order to provide a marking which will not only be clearly visible but substantially permanent and which will enable the fabric to be rolled up shortly after marking, I have devised the following improved method of marking this fabric: I first force a suitable tool through one of the meshes of the wire, thus forcing apart the strands of the wire fabric which surround this opening indicated as 4 in the drawing, and in this manner the strands of wire 5 which surround the opening are brought in closer juxtaposition than the normal strands 6 of the fabric. The marginal portion of this opening of which the strands are thus forced in closer relationship is then marked by means of a quick drying paint 7 of a contrasting and distinctive color, which paint owing to its viscosity and surface tension spans the space between the adjacent strands of wire, thus forming a marking which is easily and distinctly visible. By reason of the quick drying character of the paint which is preferably composed of a compound of gun cotton, alcohol and amyl acetate, the fabric can be

quickly rolled without danger of the paint sticking. Furthermore, by reason of the fact that the paint completely fills the interstices in the fabric surrounding the opening, this paint is applied in sufficient quantities so as to be easily visible, and by reason of the strands of wire being forced into closer proximity where the paint is applied, this paint adheres more firmly to the wire strands of the fabric and thus the marking is more permanent.

While I have illustrated and described one specific embodiment of my invention, it will be understood that I do not wish to be limited to the exact form of the invention shown and described, but that various changes and modifications may be made without departing from the spirit and intent of my invention.

What I claim as my invention is:

1. A web of wire screen cloth having, measure marks at predetermined distances and adjacent the edge thereof, each of said measure marks consisting of an enlarged opening formed by a separation of adjacent wires and a film of marking medium bridging across and filling the openings between the wires around said enlarged opening.

2. A process of applying measure marks to a web of wire screen cloth which comprises the operations of forcing a tool between the wires at predetermined intervals thereby forming an enlarged opening and crowding the wires surrounding the opening into closer proximity, and applying a quick-drying viscous marking medium to the screen around said opening thereby causing said medium to bridge across and fill the openings between the wires in the space immediately surrounding said enlarged opening.

Signed by me at Dixon, Illinois, this 20th day of July, 1921.

DOUGLAS G. HARVEY.
